[57] CLAIM

The ornamental design for a fifth wheel release pin tool, as shown and described.

DESCRIPTION

FIG. 1 is a front elevational view of the fifth wheel release pin tool of the present invention;

FIG. 2 is a rear elevational view of the fifth wheel release pin tool of FIG. 1;

FIG. 3 is a left side elevational view of the fifth wheel release pin tool of FIG. 1;

FIG. 4 is a right side elevational view of the fifth wheel release pin tool of FIG. 1;

FIG. 5 is a top plan view of the fifth wheel release pin tool of FIG. 1;

FIG. 6 is a bottom plan view of the fifth wheel release pin tool of FIG. 1; and,

FIG. 7 is a top, front, right side perspective view of the fifth wheel release pin tool of FIG. 1.
